UNITED STATES PATENT OFFICE.

EDWARD J. BROOKS, OF EAST ORANGE, NEW JERSEY, ASSIGNOR TO E. J. BROOKS & CO., OF NEW YORK, N. Y.

SEAL-PRESS, (ROLLER.)

SPECIFICATION forming part of Letters Patent No. 319,387, dated June 2, 1885.

Application filed November 3, 1884. (No model.)

To all whom it may concern:

Be it known that I, EDWARD J. BROOKS, a citizen of the United States, residing at East Orange, in the State of New Jersey, have 5 invented a new and useful Improvement in Seal-Presses, ("Roller,") of which the following is a specification.

This invention relates to improvements in sealing railway freight-cars, baggage, &c., by 10 means of "lead-and-wire" seals which have seal-disks of lead or other soft metal, that are compressed upon the ends of flexible shackles of wire extending therethrough, to securely unite the latter, after the application of the 15 seals to sealing-staples or the like, and are at the same time impressed with lettering or distinguishing-marks.

The primary object of the present invention is to facilitate thoroughly closing the thread- 20 ing-holes of the seal-disks and distinctly stamping the same, so as to avoid the imperfect pressing which results from weak or numb hands, necessary haste, and like causes. Another object of the same is to render the press 25 in part self-adjusting after each pressing operation preparatory to another. Another object thereof is to facilitate properly locating each seal-disk in the seal-press preparatory to pressing it.

30 This invention consists, first, in the combination, in a seal-press, of a segmental roller-die carried by the pivot end of a lever-handle, a corresponding segmental roller-die adapted to be carried forward by the seal-disk in the 35 pressing operation, and a spring to return the die last named to its position of rest after each pressing operation preparatory to the next; and, secondly, in the combination, in a seal-press, of a pair of lever-handles, a pair of 40 roller-dies, one of which is operated by one of said lever-handles and is adapted to admit the seal-disk freely between the dies preparatory to each pressing operation, and a gage-stop to limit such insertion of the seal-disk, substan- 45 tially as hereinafter specified.

Two sheets of drawings accompany this specification as part thereof.

Figure 1 of these drawings is a side view of a seal-press, illustrating this invention. Fig. 2 50 represents a sectional elevation thereof, showing a lead-and-wire seal therein and illustrat-

ing the pressing operation. Figs. 2^x and 2^z are perspective views of said seal, representing, respectively, its dimensions and appearance before and after the pressing operation. 55 Fig. 3 is a partial top view of the press as seen in Fig. 1, and Fig. 4 an end view thereof; and Fig. 5 is a face view of the loose segmental roller-die. Fig. 6 is a sectional elevation of another seal-press, illustrating modifications 60 of the same invention, and Fig. 7 represents, a section on the line 7 7, Fig. 6.

Like letters of reference indicate corresponding parts in the several figures.

In each of the forms represented by the 65 drawings this improved seal-press is composed of a pair of lever-handles, A B, a pair of cheeks, C C, integral with said handle A, a segmental roller-die, D, carried by said handle B, and pivoted therewith by a rivet-pin, 70 d, passing through said cheeks, a matching segmental roller-die, E, pivoted between said cheeks by a rivet-pin, e, parallel to said pin d, a spring, F, for returning said die E to its position of rest, and a gage-stop, G, integral 75 with said cheeks, to facilitate properly locating a seal-disk, S, between the dies, as illustrated by full lines in Fig. 2, and by Figs. 6 and 7. With said lever-handle B turned up and said roller-die E in its position of rest, as 80 shown in full lines in Fig. 2, and in Fig. 6, a space is formed between the latter and the upper roller-die, D, which freely admits a given size of the seal-disk S, having the ends of a shackle-wire, W, threaded therethrough, as 85 shown in Fig. 2^x. The extra depth of said space between the dies in this condition of the press is due to the retiring curve of the back of said roller-die D, or the pivot end of the lever-handle B. The die-surfaces are con- 90 centric with the respective pivot-pins d e. With the inner edge of the seal-disk S against the gage-stop G, its other edge is located beneath the front edge of the die-surface of said die D, as seen in Figs. 2 and 6. The lever- 95 handle B is now brought down, bringing said front edge of said die-surface in contact with the seal-disk in the first place, compressing it between the two dies, and extending this compression by a rolling action to the opposite edge of the seal-disk. The lower roller-die, E, meanwhile turns with the upper die, being

carried along by the seal-disk to its position indicated by dotted lines in Fig. 2. The pressed seal-disk finally emerges, having been propelled outward during the pressing operation, as indicated by the arrow *s*, Fig. 2, and said lower die is returned by the spring *F* to the position of rest, in which it is shown in full lines in Fig. 2, preparatory to the next pressing operation.

10 In the form represented by Figs. 1 to 5, inclusive, apart from immaterial details of shape, the upper roller-die, *D*, is integral with the lever-handle *B*, which to this end may be a steel casting; but malleable iron will suffice for both. The die-surfaces of both of the roller-dies *D* *E* are "engraved," as shown in Figs. 4 and 5, which may illustrate providing either or both with lettering or other marks to distinguish the seals pressed thereby. The front 20 edge of the die-surface of said upper die is roughened, as represented at *r*, Figs. 2 and 4, to insure its taking hold of the seal-disk. The spring *F* is a "flat" spring engaging with a radial lug, *l*, on said die *E*, and held at its 25 rear end within the recessed head end of the lever-handle *A* by a screw, *f*, Figs. 2 and 3. The gage-stop *G* is a central spur projecting upward from a bridge between the cheeks, and the latter is provided with a stop-notch, 30 *n*, which limits the retrogression of said die *E*, its forward motion being arrested by a lip, *m*, at the face of the press, as clearly seen in Fig. 2.

The modifications illustrated by Figs. 6 and 35 7, apart from immaterial details of shape and proportions, consist, first, in making the upper die, *D*, a distinct part of steel, held in a transverse dovetail seat in the pivot end of the lever-handle *B*, and kept in its seat by the 40 cheeks *C* *C*; secondly, in making the spring *F* a spiral spring, held within a longitudinal bore, *a*, in the lever-handle *A*, the lug *l* on the lower die, *E*, being adapted thereto, and in limiting the backward motion of said die 45 instead of its forward motion by the front lip, *m*, which is engaged at the limit of the re-

turn movement by said lug *l*, as seen in Fig. 6; thirdly, in roughening the die-surface *x* of the lower die, *E*, by file-cutting it, for example, so that it shall be carried forward without slip in pressing thin seals, the lettering or marks being confined to the die-surface of the upper die; and, fourthly, in so constructing the gage-stop *G* that it embraces the seal-disk, as best seen in Fig. 7, whereby it is better suited 55 to all sizes and kinds of lead-and-wire seals, and forms a more efficient stay to the cheeks *C* *C*, with which it is integral as in the first form. A hammer attachment, *h*, is also represented in Fig. 6, as patented by me March 7, 65 1882, (United States Patent No. 254,601.) One or more of these modifications may obviously be used without the others, and like modifications within the scope of my respective claims, hereinafter stated, will suggest themselves to manufacturers and others.

Having thus described my said improvement in seal-presses, (roller,) I claim as my invention and desire to patent under this specification—

70 1. The combination, in a seal-press, of a segmental roller-die carried by the pivot end of a lever-handle, a corresponding segmental roller-die adapted to be carried forward by the seal-disk in the pressing operation, and a spring to return the die last named to its position of rest after each pressing operation preparatory to the next, substantially as herein specified.

2. In a seal-press, the combination, substantially as herein specified, of a pair of lever-handles, a pair of roller-dies, one of which is operated by one of said lever-handles and constructed with a retiring curve at its back to admit the seal-disk freely between the dies 85 preparatory to the pressing operation, and a gage-stop to limit such insertion of the seal-disk, for the purpose set forth.

EDWARD J. BROOKS.
